UNITED STATES PATENT OFFICE.

JULIUS HALMA, OF NEW YORK, N. Y.

BOTTLE HOLDER.

Application filed April 8, 1927. Serial No. 182,109.

This invention relates to milk bottle holders and in particular to a type wherein the bottle is securely held and prevented from being removed unless the door is opened in connection with which the milk bottle holder is used.

A particular object of the invention is to provide a simplified milk bottle holder which may be used to hold one or more bottles of milk in position above the ground and so located that it is necessary for the occupant of the house to open the door before access can be had to the locking mechanism through the medium of which the bottles are imprisoned in the holder.

A still further particular object of the invention is to provide a mechanism which will operate automatically to prevent the milk bottles from being removed after they have been once positioned in the holder.

A still further particular object of the invention is to provide a device which may be made up in few parts and which will operate efficiently to securely lock the bottles in position in the holder.

To enable others skilled in the art to fully comprehend the underlying features of my invention that they may embody the same in the various modifications in structure and relation contemplated, a drawing depicting a preferred form has been annexed as a part of this disclosure and in such drawings, similar reference characters denote corresponding parts throughout all the views, of which,

Figure 1 is a view in perspective showing the location of my improved bottle holding device in a door casing, so positioned that the door must be opened before access may be had to the locking mechanism of the holder.

Figure 2 is a top plan view, partly in section showing the construction of the locking mechanism and the arrangement of the holder in conjunction with a door, which prevents the holder from being unlocked until the door has been opened.

Figure 3 is a sectional view, taken on the line 3—3 of Figure 2 showing the construction of the holder and the locking plate in its open position.

Figure 4 is a view in side elevation, partly in section showing a modified form of bottle holder arranged to hold a single bottle and so constructed also that it is necessary to open the door before the bottle can be removed, once it has been positioned in the holder, and

Figure 5 is a sectional view taken on the

line 5—5 of Figure 4 showing the construction of the bottle holder and the arrangement of the holding members which prevent rearward operation of the flat gate whereby the bottle may be withdrawn after it has once been locked in position in the holder.

Referring to the drawings in detail, my improved bottle holder consists principally in a wire frame 5, bent upwardly at its closed end as at 6 and provided in said bent up portion with the opening 7 through which screws or other holding members may be passed to securely position the holder adjacent the top of the jam 8 or casement of the door, it being of course understood that the holder is positioned so that it extends longitudinally and is positioned adjacent the door.

The outer or reception end of the holder has secured thereto the frame piece 9 which is also provided with the screw receiving openings 10 through the medium of which the holder at its forward end may be secured to the door casement. The frame piece 9 is suitably soldered or otherwise secured to the outer end of the holder rod or receptacle 5,

it of course being understood that this rod 5 is bent around and the legs thereof are separated sufficiently to allow the neck of a bottle to pass therebetween but close enough to prevent the head of the bottle from slipping therethrough or being manipulated so that the bottles may be removed from the holder without releasing the latch, as will be hereinafter explained. The front part of the frame 10 is cut out as at 11 to receive the hinged portions 12 of the latch door 13, the hinged portions of course surrounding the hinge pin 14 and holding therebetween, on such hinge pins a suitable spring 15 which has a tendency to normally raise the latch plate 13 to its open position whereby the bottles may be readily slid between the leg portions of the holder, the ends of the spring 15 co-operate with the frame piece 9 and with the latch plate 13 but when the latch plate is closed, the spring is prevented from forcing the latch plate into its open position through the medium of an eye 16 which is carried in the extended portion 17 thereof, this ex-

tended portion 17 forming a closure for the front end of a housing 18 in which the latch mechanism is positioned. This latch mechanism consists of a pivoted latch 19 which is suitably pivoted on a pin 20 extending be-

tween the upper and lower walls of the housing 18, the latch 19 being limited in its out-

ward movement by another pin 21 which is also secured between the upper and lower walls of the housing 18. The latch 19 in its mid portion carries a thumb piece 22, through 5 the medium of which the latch may be pushed inwardly into the housing 18 against the action of a coil spring 23, the spring being positioned between the side wall of the housing 18 and the back of the latch 19 and being suitably guided by the guide pin 24 carried in the 10 rear face of the latch 19, the latch at its free end engages the eye plate 16, before referred to, and thereby holds the latch plate 13 in its closed position. The side of the housing is 15 open and when the holder is placed in position on the casement of the door, it is so arranged that the door 25 forms the closure for the open side of the housing 18 and after milk bottles have been placed in the holder 5, 20 the milk man pushes the latch plate 13 down until the extension 16 thereof is engaged by the latch 19, which holds the latch plate 13 in its closed position and prevents removal of the milk bottle or bottles 26, it of course 25 being understood that the capacity of the holder is only limited by its length and that it may be designed to hold one or any number of bottles necessary.

When the occupant of the house wishes to 30 take in the milk, the latch plate 13 may be opened by pressing the thumb piece 22, the thumb piece being accessible after the door has been opened by any one in authority or having a key thereto and as soon as the latch 35 plate 13 has been released by the latch 19, the spring 15 causes the same to assume the position shown in Figure 3 and the milk bottles may be removed.

I am aware that many milk bottle holders 40 have been provided but in substantially all of these heretofore employed, some key operated means are used for imprisoning the milk bottle and in the event of the loss of the key, it is necessary to break the holder in 45 order to obtain the milk.

In my improved invention, it is evident, therefore, that when the door is opened, the latch may be operated to open the latch plate 13 and thereby allow withdrawal of the milk 50 bottles from the holder.

It is also evident the bent up portion 6 of the holder 5 is substantially the same height as the frame 9 and consequently the holder is secured to the casing at both its ends and 55 any attempt to remove the holder from the casing of the door will be frustrated.

In Figures 4 and 5, I have shown a modified form of milk bottle holder and lock, which while shown to be used to hold a single bottle, might also be adaptable to use to hold two bottles, although the number of bottles from 60 which it is designed must be the number of bottles contained therein in order to carry out the locking features thereof, and this improved milk bottle holder is attached to the

casement 8 of the door in the same manner as is the holder 5, the holding consisting of a substantially U-shaped frame piece 27 which is suitably secured in any manner, such as by riveting or soldering to the receiving end of the milk bottle holder 28. The holder 28 is provided with an open bottom, the opening being defined by inturned flanges 29 formed on the side walls 30 of the holder 28, the discharge end of the holder across the top portion thereof being closed as at 31 and being provided with suitable openings, if desired, whereby the piece 31 might be positioned on a part of the fancy casement, although in the drawings I have shown the top of the frame 27 as being provided with openings to receive the holding screws which secure the holder 28 in position on the casement so that its discharge end abuts against the door 25 and is closed when the door is closed. The under 75 side of the top 32 of the casing 27 is provided with depending spring strips 33, which at their free end are disposed in such a position as to prevent free passage of the upper end of the locking plate 34 when the same is revolved in the direction indicated by the arrow. This locking plate 34 is pivoted on the rod 35 which extends between the side walls of the frame 27, the plate covering the entrance to the frame 27 and also to the holder 28. It 80 is evident, of course, that the plate 34 having free pivotal movement on the pin 35 will give way to the entrance of a bottle when the same is pushed in on the flanges 29 of the holder 28 and when a bottle, for instance, as shown in Figure 4, has been positioned as 85 illustrated in outline, the locking plate 34 can be snapped past the spring strip 33 and the bottle being in the position shown, will prevent the locking plate 34 from being reversed 90 in its rotated direction to allow the bottles to be again drawn out of the holder, as the strips 33 project in the path of the upper end of the locking plate 34 and prevent its rotation in direction contrary to that indicated by the 95 arrow or in counter-clockwise direction.

In order therefore, for the bottle to be removed, it is necessary that the occupant of the house open the door which opens the end of the casing and allows the bottle to be drawn 100 thereout of, it of course being understood that the only work necessary in locking the bottle in position is that the milk man press on the bottom of the locking plate 34 until the upper end thereof snaps under the edges of the 105 spring pieces 33. Any number of bottles may be used in a device of this kind but the locking effect will not be obtained unless the number of bottles for which the device has been 110 designed are positioned therein so that the locking plate 34 cannot be revolved counter-clockwise to a horizontal position to allow withdrawal of any of the bottles, it being evident from inspection of Figure 4 that the bottle, when in place, prevents rotation in a coun- 115

ter-clockwise direction of the locking plate 34 and consequently the upper end of the locking plate 34 being prevented also from moving in a clockwise direction, effectively locks the bottles in position in the holder and prevents them from being stolen.

It is evident, therefore, that I have provided an improved milk bottle holder which locks the bottles in position and which needs no attention on the part of the occupant of the house and very little on the part of the person delivering the milk as the bottles, in order to be imprisoned in either holder, requires simply the latching of the holding plate 13 or 34 so that they cannot be subsequently removed from the locking end of the housing but the door must first be opened before the bottles can be removed from the holder.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claim.

Having thus described my invention, what

I claim as new and desire to secure by United States Patent is:—

A device for holding a plurality of bottles by the neck comprising a heavy wire frame, one end of which has openings therein and which is turned upwardly, a frame piece secured to the wire frame and having openings therein, the openings in the frame and frame piece being provided for the reception of screws arranged to hold the device in place against the top of a door casing, a latch plate pivoted on the frame piece and arranged to close one end of the wire frame, a spring for normally urging the plate open, a latch housing at one end of the frame piece, one side of which is closed by the end portion of said latch plate, an eye carried by the plate and extending into the latch housing, a latch, a spring cooperating with the latch for normally urging the same into engagement with the eye whereby opening of the plate is prevented, a finger piece on the latch, a pin for limiting the movement of the latch, and the device being so arranged relatively to a door that access to the finger piece side of the latch housing is prevented by the door when the same is closed.

In testimony whereof I affix my signature.

JULIUS HALMA. [L.s.]
